UNITED STATES PATENT OFFICE.

FRED O. DOYLE, OF ST. LOUIS, MISSOURI.

AUTOMATIC FIRE-LIGHTER.

1,321,995.

Specification of Letters Patent. Patented Nov. 18, 1919.

Application filed April 7, 1919. Serial No. 288,205.

To all whom it may concern:

Be it known that I, FRED O. DOYLE, a citizen of the United States, residing at the city of St. Louis and State of Missouri, have 5 invented a new and useful Automatic Fire-Lighter, of which the following is a specification.

This invention relates to automatic fire lighters.

10 An object of the invention is to provide a device controlled by a timing element to effect ignition of combustible material at any predetermined time.

15 Another object of the invention is to provide a device of the character mentioned comprising a frame arranged to support a clock and an ignition element, in combination with means controlled by a part of the clock for causing ignition of the ignition 20 element at any predetermined time.

Other objects will appear from the following description in which reference is made to the drawings showing an appropriate form of the invention, and in which—

25 Figure 1 is a side elevation.

Fig. 2 is an elevation viewed from another side.

30 Fig. 3 is a plan view of the supporting device by which the lighter may be supported in connection with a stove or the like.

Fig. 4 is a detailed view showing the releasable latch controlled by the timing element to release the ignition device at a predetermined time.

35 The frame of the device consists of an upright member 1 having an arcuate portion 2, and a separate arcuate member 3 having its lower end overlapping the end of the member 2 and connected therewith by a screw

40 4 attached to the end of the member 3 and extending through a slot 5 in the end of the arcuate portion 2. A thumb nut 6 is in threaded engagement with the screw bolt 4 and is operable to clamp two parts together, 45 or to release them as desired.

The upper end of the arcuate member 3 is formed with an upward extension 7 parallel with the upright member 1. A bracket 8 has one end secured between the upright member 50 1 and the extension 7 and carries near its outer end a pivoted pawl 9. The pawl 9 has one arm which is in the path of movement of a hammer 10 which is controlled by the clock in the usual manner, so that said hammer 55 will be operated after any predetermined time.

An arm 11 has one end between the upright 1 and a plate 12, said arm being pivotally mounted on a screw bolt 13 passing through the upright 1 and the plate 12 and 60 having a winged nut 14, whereby the arm 11 may be clamped and securely held in any desired adjustment. The arm 11 pivotally supports a clamping device 15 by which the lighter can be supported in connection with 65 a stove, or in any other place. The jaws of the clamping device 15 may be pressed together by a winged nut 16 operating on a screw 17.

The upper end of the upright 1 is formed 70 with a lateral extension 18 having a roughened surface 19 for causing ignition of a match when moved by the lighting device.

A match supporting arm 20 is pivoted upon a bracket 21 and has a projection 22 75 near its lower end formed with a notch 23 adapted to be engaged by the hook of the pawl 9. A retractile spring 24 connects the arm 20 with the upright 1 above the supporting bracket 21. A socket 25 on the upper 80 end of the arm 20 receives and holds a match so that when the arm 20 is released from the latch 9, retraction of the spring 24 will draw the arm 20 toward the upright 1, causing the head of the match to be ignited 85 as a result of frictional contact with the abrading surface 19. A support 26 secured to the upright 1 is intended to support a match or combustible material 27 in position to be ignited by the burning match supported by the arm 20 when said arm moves to the position shown by dotted lines in Fig. 1.

From the foregoing it will be understood that I have provided a simple, durable and efficient device which entirely fulfils its function. I do not restrict myself to unessential features of construction, but what I claim and desire to secure by Letters Patent, is:—

1. A device of the character described, comprising a frame, means for supporting 100 a timing mechanism in said frame, an upright member in connection with said frame, a lateral extension on said upright member, an abrading surface on said extension, a bracket attached to said upright member, an 105 arm pivotally supported by said bracket, a spring connecting said arm with said upright for drawing said arm to one position, a bracket supported by said frame adjacent to the timing mechanism, a pawl on said 110 last-named bracket for holding said arm in one position in opposition to said spring and

arranged to be released by a part of the timing mechanism, and means for supporting a match by said arm in position to be moved against said abrading surface.

5 2. A device of the character described, comprising a frame, means for supporting a timing mechanism in said frame, an upright member in connection with said frame, a lateral extension on said upright member, 10 an abrading surface on said extension, a bracket attached to said upright member, an arm pivotally supported by said bracket, a spring connecting said arm with said upright for drawing said arm to one position, 15 a bracket supported by said frame adjacent to the timing mechanism, a pawl on said last-named bracket for holding said arm in one position in opposition to said spring and arranged to be released by a part of the 20 timing mechanism, means for supporting a match by said arm in position to be moved against said abrading surface, and means for supporting a combustible material by 25 said upright member in position to be ignited by said match.

3. A device of the character described, comprising an upright member, an arcuate member in connection with said upright member, a second arcuate member arranged 30 to coöperate with the first-named arcuate member to support a timing mechanism,

means for supporting combustible material by said upright member, a pivoted arm, a spring for operating said arm, a latch for holding said arm in one position in opposition to said spring and arranged to be released by operation of a part of the timing mechanism after a predetermined time, 35 means for supporting a match by said arm, and means for causing ignition of said match when said arm is moved by said spring after said latch device is released. 40

4. A device of the character described, comprising an arcuate member, a second arcuate member, means for clamping said 45 arcuate members together to support between them a timing mechanism, an upright member in connection with one of said arcuate members, a lateral extension on said upright member, an abrading surface on 50 said extension, an arm pivotally supported by the upright member, a spring for drawing said arm to one position, a latch device for holding said arm in one position in opposition to said spring and arranged to be 55 released by a part of the timing mechanism, means for supporting a match by said arm in position to be moved against said abrading surface, and means for supporting a combustible material by said upright member in position to be ignited by said match. 60

FRED O. DOYLE.
